CLAIM

The ornamental design for a vaporizer device, as shown and described.

DESCRIPTION

FIG. 1 is a bottom, front, and right side perspective view of an embodiment of a vaporizer device of our design; FIG. 2 is a top, rear, and right side perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is a bottom, front, and right side perspective view thereof showing our design in an environment in which it may be used. The broken lines in the drawings depict portions of the vaporizer device that form no part of the claimed design.

1 Claim, 6 Drawing Sheets
